Patented Jan. 7, 1919.

UNITED STATES PATENT OFFICE.

WALTER DEWITT KEMP, OF NEW YORK, N. Y.

DEVICE FOR SHAVING.

1,290,228.

Specification of Letters Patent. Patented Jan. 7, 1919.

Application filed March 30, 1917. Serial No. 158,507.

To all whom it may concern:

Be it known that I, WALTER DEWITT KEMP, a citizen of the United States, residing at New York, county of New York, 5 State of New York, have invented certain new and useful Improvements in Devices for Shaving, of which the following is a specification.

My invention relates to a device for shaving, such as a razor, and has for its object the combination with a shaving blade of means whereby the blade may be secured and held in a desired position and of means whereby the device may be engaged and the 15 blade controlled by a finger of the user, when in use.

Considerable danger as well as difficulty is encountered in shaving with the old style razor on account of the tendency of the 20 blade to continually move with reference to its angle to the handle and with reference to its angle to the face, while being used.

I am aware that it is old in the art to provide securing means for holding the 25 blade at a certain angle to the handle during the operation of shaving, and I do not claim this broadly, but only the specific auxiliary means in combination therewith for guiding and controlling the blade as hereinafter set 30 forth, and more particularly with reference to the angle of the blade to the face. In my improved combination means are provided whereby the razor may be held by the hand in a natural position and the blade secured 35 or locked at the desired angle with reference to the handle and whereby the finger of the user is utilized (through members of the combination provided) in facilitating the control of the blade with reference to its 40 angle to the face during the operation of shaving, in such a manner that any part of the face may be shaved easily and safely.

These objects I accomplish by means of such structure and relative arrangement of 45 parts as will appear by a perusal of the specification and claims, and by reference to the accompanying drawings, which illustrate one adaptation or embodiment of my invention, in which:

50 Figure 1 is an open side view of a razor showing an adaptation or embodiment of my device;

Fig. 2 is a closed side view of a razor showing an adaptation or embodiment of 55 my device;

Fig. 3 is a section on the line 3—3 of Fig. 1;

Fig. 4 is a partial plan of Fig. 2; and, 60 Fig. 5 is a sectional view on the line 5—5 of Fig. 2.

Similar numerals of reference indicate corresponding parts in the several views.

Referring to the drawings, the numeral 1 designates a razor handle, carrying a blade 2, secured by a pivot 5. The numeral 3 designates a plate attached to the handle by means of pins or anchoring devices 12, which plate is provided with a gripping arm or member 8 pivotally secured thereto by the rivet or bearing 7. The arm 8 is provided 70 with a gripping jaw 10 and an extension 13 with its inward projection 9, which projection 9 is adapted to register with and engage the slots 4 and 6 of the plate 3. 11 designates the end of the tang of the blade, 75 it being engaged by the gripping jaw 10, as more particularly shown in Fig. 1.

The extension 13 of the arm 8 is slightly raised or convex, thereby forming a resilient bearing having a spring effect with reference to its inward projection 9, so that the projection 9 is pushed inwardly onto the plate 3 over which it travels. It will thus be seen that when the inward projection 9 is directly opposite either of the slots 4 or 6 85 it will register with or engage the slot. The gripping jaw 10 at the opposite end of the arm 8 is thereby held in engagement with the tang end 11, in a fixed and controlled manner, when the projection 9 registers with 90 the slot 6, as shown in Fig. 1. Similarly, when the projection 9 registers with and engages the corresponding slot 4 the arm 8 with its gripping jaw 10 is held in a disengaged and controlled position, as when not 95 in use, as shown in Fig. 2.

It is obvious that the resiliency of the extension 13 provides sufficient spring to lock or hold the arm 8 in position, yet the member 13 is sufficiently resilient to permit the 100 projection 9 to be moved out of slot engagement when pressure is applied to the opposite end of the arm 8, as simply pushing sharply with the finger. It will be seen that the end of the tang 11 is engaged by the 105 gripping jaw 10 when the extension 13 with its projection 9 has traveled over the surface of the plate 3 until the projection 9 registers with or engages the slot 6, whereby the blade is secured, and is ready for use; 110

- said traveling of the projection 9 over the plate 3 being easily effected by pulling on the arm 8 or gripping jaw 10 with the thumb and finger.
- 5 The approximately triangular space 14 now formed provides a space for a finger, as the third finger of the hand, which finger engaging the boundaries of the approximately triangular space 14, viz: the handle 10 of the razor, the tang of the blade, and the arm of the device, assists very materially in holding, controlling and operating the razor, especially at the desired angle with reference to the face, making the operation of shaving easier and of practically no danger, as it has been found with the finger in this engagement the user easily prevents the blade cutting the face, and has a very much finer control of the cutting edge.
- 15 20 When it is desired to disengage the jaw 10 from the end of the tang 11, all that is necessary is to pull outwardly on the arm 8 or the jaw 10. Simultaneously, the projection 9 of the extension 13 is forced out of its slot 6, the tang is released from its engagement with the jaw 10, and the blade may be closed. By now pushing the arm 8 the opposite way, *i. e.*, inwardly, the projection 9 is caused to again drop into and out of its slot 6 and 25 follow its path across the plate 3 until it registers with and engages the slot 4, whereby the device is held in a normal disengaged and closed or folded position, as shown in Fig. 2.
- 30 35 The plate 3 may be constructed slightly convex, to augment the engaging of its slots 4 and 6 with the projection 9; and the actuating, controlling and securing device for the blade in combination with its handle 40 may be attachable and detachable to and from its operative co-action in each case so that it may be combined and removed in its employment with any razor of ordinary type in an attachable and detachable manner.
- 45 50 55 The engaging jaw may be located at any suitable point or points, and may comprise a single or plurality of engagement means, so that the angle of the shaving blade member may be adjusted and controlled at various suitable angles, the illustration showing only one gripping jaw for simplicity and to avoid confusion in the conception of the invention.
- The device may be constructed of any suitable kind of material and may be made in any size or shape desired to suit different sizes and styles of razors, so long as the various members of the combination co-act

and coöperate to perform the functions and produce the results desired, without departing from the spirit of the invention. 60

Having now described my invention, what I claim as new and desire to secure by Letters Patent is:

1. In a device of the class described, the combination with a razor, of an arm pivoted to the handle of said razor, and a gripping jaw formed at the free end of said arm adapted to engage with the tang of the blade of said razor when extended, said arm, tang and handle forming a triangle adapted to receive one of the fingers of an operator. 65

2. In a device of the class described, the combination with a razor, of a spring arm pivoted to the handle thereof, said arm being adapted to fold closely against said handle or be extended at an angle thereto at the front, a gripping means formed at the free end of said arm adapted to engage the tang of the razor-blade, and means for securing 75 said arm in either of its adjusted positions. 80

3. In a device of the class described, the combination with a razor, of an arm pivoted to the handle of said razor, said arm being bent so that its free end is normally in register with the center of said razor, a gripping jaw formed with the free end of said arm adapted to engage with the end of the tang of the blade of said razor when in an extended position, said arm, tang and handle 90 forming the sides of a hollow triangle disposed on the front side of said razor, and means for securing said arm in either an operative or inoperative position. 95

4. In a device of the class described, the combination with a razor comprised of a handle, a blade pivoted therebetween and a tang extending opposite to said blade, of a plate secured on the exterior of said handle, an arm pivoted in said plate, an extension 100 formed with said arm adapted to engage in either of two openings in said plate, and an offset gripping jaw formed at the opposite, free end of said arm engageable with the end of said tang, said arm when extended forming in combination with said handle and tang, a hollow triangle, and being foldable closely adjacent to said handle when said razor blade is folded. 105

In testimony whereof, I have hereunto 110 subscribed my name in the presence of two witnesses, this 20th day of March, 1917.

WALTER DEWITT KEMP. [L. s.]
